The ornamental design for a waterproof LED power bank, as shown and described.

DESCRIPTION

FIG. 1 is a front, top perspective view of the waterproof LED power bank, showing my new design;

FIG. 2 is a rear, bottom perspective view, thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of a portion indicated with numeric 9 in FIG. 1.

The broken lines shown in the drawings represent portions of the waterproof LED power bank that form no part of the claimed design.
